UNITED STATES PATENT OFFICE.

IVAN ROČIĆ, OF CHICAGO, ILLINOIS.

BARKING-MACHINE.

1,333,734.

Specification of Letters Patent. Patented Mar. 16, 1920.

Application filed February 16, 1917. Serial No. 149,104.

To all whom it may concern:

Be it known that I, IVAN Ročić, a subject of the Emperor of Croatia Austria, Hungary, and a resident of the city of Chicago, 5 county of Cook, and State of Illinois, have invented certain new and useful Improvements in Barking-Machines, of which the following is a specification.

My invention relates to improvements in 10 barking machines adapted to remove the bark from the sections of logs and has for its object the provision of an improved construction of this character which has efficient operation.

15 The invention consists in the combinations and arrangements of parts hereinafter described and claimed.

The invention will be best understood by 20 reference to the accompanying drawings forming a part of this specification, and in which,

Figure 1 is a longitudinal section, shown 25 partially in elevation, of a barking machine embodying my invention,

Fig. 2, a transverse section of the same, and

Fig. 3, a top plan view of the same.

The preferred form of construction as 30 illustrated in the drawings comprises an open work barking drum made up of a plurality of sets of longitudinal angle irons 5 and 6 arranged to alternate with each other with one of their legs arranged circumferentially or on the periphery of the drum and 35 the other legs projecting at an acute angle inwardly with reference to the periphery. The upwardly projecting legs of the angle irons 5 are materially longer than the corresponding legs of the angle irons 6 as 40 shown. By this arrangement the high points or rough protuberances on the logs or blocks to be treated will be treated by the shorter legs of angle irons 6, while the main body or more uniform portions thereof are 45 simultaneously treated by the adjacent angle irons 5, thus adding materially to the efficiency of the machine. The angle irons 5 and 6 are arranged to alternate with each other and are secured in position by means 50 of annular angle irons 7 riveted thereto, spaces being left between said angle irons 5 and 6 to form an open work drum to permit of the ready circulation of water there- 55 through. At intervals bearing rings 8 are secured to the periphery of the drum be- tween adjacent angle iron rings 7, said rings

being arranged to rest and run upon flanged supporting rollers 9 secured to a shaft 10 traversing the lower portion of a suitable vat or vessel 11 for containing the usual water used in the barking process, said shaft 10 being driven through the medium of a pulley 12 arranged on the outside of the vat 11. Additional flanged rollers 13 are arranged at the opposite sides of the vat 11 on 60 suitable shafts 14 to contact with the rings 8 slightly below the horizontal diametric plane of the barking drum, said rollers 13 thus serving to partially support the drum and also to position the same centrally over 65 shaft 10. The barking drum is provided centrally with an annular gear 15 secured to the periphery thereof between two of the annular angle irons 7, said gear meshing with the pinion 16 secured to shaft 10. By 70 this arrangement it will be observed that the barking drum is given a sort of a floating bearing on the vat 11 and may be rotated with the expenditure of a minimum amount of power.

80 The barking drum is further stiffened and strengthened by means of peripheral angle iron braces 17 and suitable inlet and outlet aprons 18 and 19 are provided for insertion and discharge of the log sections 85 in the usual manner.

The vat 11 is provided centrally with a depression or well 20 into which the removed and pulverized bark, fibers and particles will be deposited and an inclined 90 trough or chute 21 leads upwardly and laterally from said well. An endless chain conveyer 22 is arranged to operate in well 20 and trough 21, being operated by means of the shaft 23 driven by a belt 24 as indicated. A drain 25 leads from the bottom of well 20 and is controlled by means of the valve 26, a grate 27 being arranged over the entrance to said drain to prevent clogging thereof by bark particles. By this arrangement it will be seen that the bark removed from the log sections will gather and settle in the well 20 and will be removed therefrom by the action of conveyer 22 independent of the action of the barking drum, thus accomplishing such removal with great thoroughness and efficiency. When desired the well 20 may be readily drained and cleaned.

100 While I have illustrated and described the preferred form of construction for carrying 110 my invention into effect, this is capable of variation and modification without depart-

ing from the spirit of the invention. I, therefore, do not wish to be limited to precise details of construction set forth, but desire to avail myself of such variations and 5 modifications as come within the scope of the appended claims.

Having described my invention what I claim as new and desire to secure by Letters Patent is:

10. 1. A barking machine comprising a rotatable drum having inwardly projecting members at the periphery thereof, said members being arranged in alternating sets of different heights, substantially as described.
15. 2. A barking machine comprising a rotatable drum having walls thereof formed of longitudinal angle irons having one of their legs arranged circumferentially and the other legs projecting inwardly, and said inwardly projecting legs being arranged in 20 alternating sets of different heights, substantially as described.
25. 3. A barking machine comprising a rotatable drum having walls thereof formed of longitudinal angle irons having one of their legs arranged circumferentially and the other legs projecting inwardly at an acute angle, and said inwardly projecting legs being arranged in alternating sets of different 30 heights, substantially as described.
35. 4. A barking machine comprising a rotatable drum having annular angle irons defining the circumference thereof, and longitudinal angle irons having one of their legs secured to the inner edges of said annular irons, the other legs of said longitudinal irons projecting inwardly at an acute angle, said inwardly projecting legs being arranged in 40 alternating sets of different heights, substantially as described.
45. 5. A barking machine comprising a drum; supporting rollers positioned substantially centrally under said drum and contacting with the periphery thereof; and positioning rollers on each side of said drum arranged to hold the same in position on said supporting rollers, substantially as described.
50. 6. A barking machine comprising a drum; supporting rollers positioned substantially centrally under said drum and contacting with the periphery thereof; positioning rollers on each side of said drum arranged to hold the same in position on said supporting rollers; and means engaging the periphery 55 of said drum for rotating the same, substantially as described.

7. A barking machine comprising an openwork drum made up of a plurality of sets of longitudinally arranged angle irons secured together by annular angle irons 60 riveted thereto; bearing rings secured at intervals around the periphery of said drum; a driving shaft arranged under said drum and carrying flanged rollers engaging said bearing rings; additional flanged rollers arranged on opposite sides of said drum and bearing against said rings; an annular gear arranged centrally on said drum; and a pinion on said driving shaft meshing with said annular gear, substantially as described. 70

8. A barking machine comprising an openwork drum made up of a plurality of sets of longitudinally arranged angle irons secured together by annular angle irons riveted thereto; bearing rings secured at 75 intervals around the periphery of said drum; a driving shaft arranged under said drum and carrying flanged rollers engaging said bearing rings; additional flanged rollers arranged on opposite sides of said drum and bearing against said rings; an annular gear arranged centrally on said drum; a pinion on said driving shaft meshing with said annular gear; a vat partially inclosing and supporting said drum and provided centrally in the bottom thereof with a well; and an endless chain conveyer leading from said well, substantially as described. 85

9. A barking machine comprising an openwork drum made up of a plurality of 90 sets of longitudinally arranged angle irons secured together by annular angle irons riveted thereto, said longitudinal angle irons being arranged in alternating sets having inwardly projecting legs of different heights; 95 bearing rings secured at intervals around the periphery of said drum; a driving shaft arranged under said drum and carrying flanged rollers engaging said bearing rings; additional flanged rollers arranged on opposite sides of said drum and bearing against said rings; an annular gear arranged centrally on said drum; and a pinion on said driving shaft meshing with said annular gear, substantially as described. 100

In testimony whereof I have signed my name to this specification in the presence of two subscribing witnesses.

IVAN RÖCIC.
